Attorney

1. A furnace for use in a building, and particularly in a magazine, having a base portion 25, which is of square configuration and has a top 11a, bottom 12, three side walls 13, 14, 15 all of square or rectangular shape, made of metal plate, and a front door 16 hinged as at the bottom at 17, also of metal plate. The entire housing is raised slightly above the floor and stands on feet or supports 18, which may be constituted of channel iron.

Along each side wall 14 and 15 is provided a funnel-shaped air conduit 19 with a wide opening 19a at the top and narrowing downwardly towards the bottom 12, where it is closed. At different heights across the housing walls 14 and 15 are provided several transverse slots 20 which form air ports, leading from said conduits 19. Over each of the ports is furnished a slanting guard plate 21, the function of which is to give the air stream a downward direction and keep out dirt and dust.

The furnace proper 10 consists of a base portion 25, which is of square configuration and

MAGAZINE TYPE HOT-AIR HEATER

Harry Barlow, Freeman, W. Va.

Application August 26, 1946, Serial No. 693,069

2 Claims. (Cl. 126—68)

1

Furnaces of present day type are generally more roomy at the top than at the bottom which has the disadvantage that the burning coal forms a crust at the top and prevents unburned coal from falling down on the grate which often puts out the fire. The aim of this invention is now to avoid this disadvantage by reversing the conditions. For that purpose I provide a furnace which is pyramidal in shape, that is to say, it is considerably more roomy at the bottom than at the top. This allows for the swelling of the burning coal which then automatically drops down on the grate, resulting in more complete combustion.

The pyramidal furnace is enclosed in a housing of cubical shape, provided with conduits for leading outside air up to near the top of the furnace, thus keeping it comparatively cool and then leading the air down the inclined furnace sides to be heated before it is distributed in the room.

In the accompanying drawing, one embodiment of the invention is illustrated. Like numerals relate to the same details in the different views.

Figure 1 is a partial vertical section of the heater with the front wall removed;

Figure 2 is a side elevation of the heater in Figure 1; and

Figure 3 is a horizontal section on a plane along line 3—3 of Figure 2.

This heater consists of two main parts, namely, a furnace proper 10 and a surrounding housing 11 therefor.

The latter is box-shaped having the top 11a, bottom 12, three side walls 13, 14, 15 all of square or rectangular shape, made of metal plate, and a front door 16 hinged as at the bottom at 17, also of metal plate. The entire housing is raised slightly above the floor and stands on feet or supports 18, which may be constituted of channel iron.

Along each side wall 14 and 15 is provided a funnel-shaped air conduit 19 with a wide opening 19a at the top and narrowing downwardly towards the bottom 12, where it is closed. At different heights across the housing walls 14 and 15 are provided several transverse slots 20 which form air ports, leading from said conduits 19. Over each of the ports is furnished a slanting guard plate 21, the function of which is to give the air stream a downward direction and keep out dirt and dust.

The furnace proper 10 consists of a base portion 25, which is of square configuration and

2

stands upon the housing bottom plate 12, which is perforated as at 12a for admitting combustion air into the ash pit 26, formed in said base portion 25 and above which is placed the grate 27 of any conventional type. A suitable tray or pan, not shown, may be placed in the pit 26 to receive dropping ashes from the grate.

On top of the base 25 and as a continuation thereof, four upwardly narrowing walls form 10 a hollow frustum of a pyramid with two side walls 28, front wall 29 and rear wall 30. The top of the pyramid is closed by a removable cap 31, thereby providing a closed combustion chamber and fire box from which the only outlet 15 is the stove pipe 32 for smoke. The cap 31 is spaced from the roof of the box or housing 11 sufficiently to permit cleaning of the furnace.

The front side 29 has a door 33 for filling the fire box and corresponding thereto, another flap 20 or lid 34 on the front door 16 of the housing 10, and near the bottom thereof a small ash pan door 35.

The relative positions of the conduits 19 as regards the pyramid side walls 28 of the furnace 25 10 are such that a space 37 is provided therebetween. Cold air is thus caused to pass upwardly from near the floor as at 38 of the room wherein the heater is located and leaves the conduits at different heights through the ports 21. The cool air will thus be heated as it is drawn up over the inclined walls 28, 29 and 30 being heated in the passage, and will collect in the upper part of the housing and be discharged down through the outlets 20.

This will result in a more even heating of a room than what is possible with ordinary heating systems, which permit the warm air to go direct up to the ceiling, furnishing no heat around the base of the heater.

Another advantage of my heater resides in the fact that cool air is delivered from the outside around the top of the furnace, so that the portion thereof above the fire box becomes cooled, which provides for a better combustion. It is of advantage to provide a small pipe 40 about one inch 45 in diameter, leading downwardly from about the middle portion of the conduit 19 into the fire box, over the top of the fire. This will keep combustion gases down, thus providing for more complete combustion.

For regulating the draft in the furnace 10, the upper end of a chain 41 can be reached from the outside of the housing 11 for raising or lowering the usual draft door.

It is to be understood that the invention as

herein disclosed may be varied from the details described and shown without departure from the spirit of the subjoined claims.

I claim:

1. An air heater of the character described, comprising a fuel combustion furnace having a base portion and an upwardly tapering top portion, a horizontally disposed grate separating the base portion and the top portion, a housing enclosing the furnace and including a bottom upon which said base portion is mounted, means supporting said bottom on an underlying supporting surface, the interior dimensions of the housing being materially greater than those of the furnace whereby an air space is provided in the housing around the furnace, air inlet means in said bottom leading into the base of the furnace, air inlet means in said bottom leading into the air space, means for carrying off products of combustion from the furnace, partition walls within the housing resting upon said bottom and extending upwardly at an inward inclination through the air space in spaced parallel relation with the tapering upper portion of the furnace, said partitions dividing the air space into inner air passageways and outer air passageways, the partitions terminating short of the top of the furnace and the second mentioned air inlet means opening only into the inner air passageways, and means providing air outlets for the outer air passageways, said outlets being located in planes disposed a substantial distance below the horizontal plane of the tops of the partitions.

2. An air heater comprising a housing having top, bottom and side walls, one of said side walls being movable to provide a door, a fuel combustion furnace within the housing and having a

base portion resting upon said bottom wall and an upwardly tapering top portion, the furnace being spaced from the walls of the housing to provide an air space around the furnace, said tapering top portion having its top terminating short of the top wall, a products of combustion outlet connected with the furnace, said bottom having air inlet openings certain of which communicate with the interior of the furnace through said base and the other openings leading into the air space, vertical partitions in the air space extending from the bottom wall to a height less than the height of the furnace and dividing the air space into inner and outer air passageways, the said other air openings communicating only with the inner air passageways, outwardly and downwardly directed heated air discharge means leading from the outer air passageways through certain of the side walls of the housing, the upwardly tapering top portion of the furnace being in the form of a frustum of a pyramid, the top of the frustum being open, and a removable cover resting upon the top of and closing the said top portion of the furnace.
